UNITED STATES PATENT OFFICE.

GEORGE L. THOMPSON, OF CHICAGO, ILLINOIS.

DESIGN FOR A BICYCLE-FRAME.

SPECIFICATION forming part of Design No. 30,500, dated April 4, 1899.

Application filed January 13, 1899. Serial No. 702,107. Term of patent 7 years.

To all whom it may concern:

Be it known that I, GEORGE L. THOMPSON, of Chicago, county of Cook, and State of Illinois, have invented and produced a new and original Design for a Bicycle-Frame, of which the following is a specification.

My novel design relates to a bicycle-frame of the type generally known as a "safety-frame," and its characteristic or essential feature consists of a triangular formation of the rear frame bars or tubes, as shown in the accompanying drawings, in which—

Figure 1 is a perspective view of a bicycle-frame embodying my novel design, and Fig. 2 a sectional detail taken on line 2 2 of Fig. 1.

In the drawings, A designates the frame as a whole; A', its rear stays, which extend downwardly and rearwardly from the seat-post cluster a, and A² the rear forks, which extend rearwardly from the crank-hanger a' to form a juncture with the stays A' at a². Both the stays and forks are made triangular in cross-section, as shown in Fig. 2, the apex of the triangle being directed outwardly. The

triangular formation of the stays is herein shown as commencing at a point a³ a little distance below the seat-post structure and extends thence down nearly to the juncture a² of the forks and stays. In a similar manner the triangular formation of the rear forks A² is herein shown as commencing at a point a⁴ a little distance to the rear of the crank-hanger and extending thence back to said juncture a². Aside from this the frame is of the usual construction and need not be more particularly described.

I claim as my new and original design—

The design for a bicycle-frame, substantially as herein shown and described.

In testimony that I claim the foregoing as my invention I affix my signature hereto, in the presence of two subscribing witnesses, this 21st day of December, A. D. 1898.

GEORGE L. THOMPSON.
